chine Co., a corporation of Illinois

Application September 22, 1943, Serial No. 503,425

2 Claims. (Cl. 235—92)

1

This invention relates to an electron switch and in particular to such a switch for use in amusement games. In such games it is often desirable to energize a circuit such as, for example, closing a relay, upon the passage of an object, such as, for example, a playing ball, where such playing ball may be metallic or non-metallic.

In the majority of such applications mechanical switches are satisfactory, and numerous such devices are in common use. An alternate method of accomplishing the desired result, i. e., energizing a circuit by the passage of an object such as a playing ball, is by the use of photoelectric cells and a light beam, where the passage of the ball interrupts the light beam and provides the necessary impulse to energize a registration circuit. This photoelectric method has been used to some extent in amusement games. However, there are certain disadvantages to the photoelectric method, one of which is that ambient light must be compensated for if the device is to be sensitive under all conditions of ambient light. This is particularly so when an amusement device is placed in such a position that it is exposed to strong daylight during a portion of the time it is in use, and operated in reduced illumination of artificial source at other times.

As a practical matter, any such triggering device used in an amusement game must be reliable under all conditions and not subject to variation by such conditions as ambient light. A further method which has been considered for use as a triggering device in an amusement game is the so-called capacity control circuit. While such devices can be made self-compensating and relatively sensitive to the passage of the playing ball, extreme accuracy of construction is necessary in order to permanently maintain such a capacity controlled circuit in a sensitive condition, and an additional disadvantage is that all such capacity controlled circuits are sensitive to body capacity, i. e., any external capacity to ground.

It is very difficult, if not impossible, to so design a capacity control triggering device so that it is not affected by external capacity to ground, provided such external capacity to ground and in particular body capacity, i. e., placing the hand of the player near the capacity control electrode or antenna, is larger than the capacity change produced by the passage of the playing ball.

For practical reasons this body capacity is always larger than the capacity change produced by the passage of the playing ball, and for this reason capacity control circuits are not practical for use in amusement games, without resorting to

5

special precautions, such as shielding electrodes or providing a large distance between the exposed electrode or antenna and the nearest position of the player. In general, it is impossible to maintain a distance of more than several inches between the exposed electrode or antenna and the nearest position of the player and, while shields may be interposed between the exposed electrode or antenna and the nearest position of the player, these shields act to partially obscure the playing board and are therefore undesirable.

This invention discloses a method of triggering a control circuit in an amusement device where the principle of operation is in part based on capacity change. In practice the control circuit herewith disclosed is economical to manufacture and absolutely reliable. It is not affected by ordinary changes of temperature, humidity, light, external magnetic or electrostatic fields, and it is relatively insensitive to external capacity to ground, i. e., body capacity, so that false operation will not occur from body capacity effects.

As previously mentioned, amusement games have been operated to a large extent with mechanical switches. Some of these switches have been perfected to a high degree, so that they make contact with very slight pressure, but regardless of how slight the pressure required to operate such a mechanical switch, there are conditions under which no mechanical switches are satisfactory. By way of one specific example, U. S. Patent Number 2,318,169 to Larock describes a twin hockey game which is operated by two players. Mechanical switches are used throughout in this game. A totally different effect could be achieved in such a game if it were possible to record the passage of the playing ball as it crosses a given point on the playing board. For example, a twin tennis game could be constructed

35 in such a manner that the score was dependent on the number of times each player's ball crossed a center line on the playing board, where said center line was analogous to the net in ordinary lawn tennis. For this purpose mechanical switches are not satisfactory. This is so because, regardless of how light a pressure may be required to operate such a switch, it must of necessity, slow down the playing ball and it may also possibly deflect the course of the playing ball. A further consideration is that in such a game the playing balls move at relatively high speed, on the order of 20 to 30 feet per second, and at such speeds mechanical switches are not reliable.

55 In the present invention, a feedback circuit is

used in combination with an especially designed electrode so that the degree of feedback is increased by the passage of any object, such as, for example, the playing ball normally associated with amusement games of the class herein referred to, this increased feedback producing a direct current pulse which is further used to trigger a gas filled discharge tube which in turn operates an associated registration means to suitably register the passage of the playing ball. Triggering and subsequent registration may be secured by the passage of any object through the electric field associated with the electrode. While the playing ball is normally metallic, for purposes of the present invention, metallic playing balls are not necessary, as trigger action may be secured by the passage of any object, metallic or non-metallic. By way of example, the playing ball may comprise a steel ball as normally used, a glass marble or a plastic ball. Similar trigger action will be secured regardless of the material of which the playing ball is made.

The primary object of this invention is to provide a control or triggering device for use in an amusement game, where said control device is not dependent on mechanical movement of any kind and where said control device is insensitive to any external influence and where the electrode associated with the said control device is so arranged as to present no mechanical obstacle to the passage of the playing ball and where said control device may be triggered only by the passage of the playing ball.

A further object of this invention is to provide two or more such control devices together with their associated electrodes and registration means so that the direction of travel of the playing ball may be recorded.

This invention is a modified form of the invention disclosed by my co-pending patent applications entitled "Electronic measuring instrument," filed September 17, 1943, Serial Number 502,843, now Patent No. 2,428,700, and "Electronic control device," filed September 20, 1943, Serial Number 503,163, both of these inventions utilizing the feedback principle in combination with a shielded electrode of special design. The present invention deals with modifications and improvements of such a nature that the principles disclosed by the aforementioned patent applications may be utilized as an electronic control switch in amusement games.

The present invention is also similar in object to my co-pending patent application entitled "Electronic switch," filed September 22, 1943, Serial Number 503,424, now abandoned, but the principle of operation, while similar, is sufficiently different as to be only loosely related. For a better understanding of the present invention, reference should be made to the above cited applications.

It is well known in the art that any amplifier will oscillate if the output of said amplifier is coupled to the input of said amplifier, providing sufficient energy is fed back from the output side of said amplifier to the input side of said amplifier. This must always be so, irrespective of whether such feedback is obtained capacitively, inductively, resistively or by other means. It is also well known in the art that the frequency of oscillation in this case will be determined by the circuit constants and that said frequency may be made any value desired by proper selection of said circuit constants.

As previously stated, numerous electronic

measurement and control methods have been based on this feedback principle. Briefly, the present invention discloses a method of producing a feedback voltage by the use of two electrodes, one connected to an output of an amplifier and the other connected to the input of said amplifier, said electrodes being so shielded from each other that with all circuit values properly adjusted zero or minimum oscillation occurs. For this condition, any object introduced in the electric field associated with the electrode will increase the feedback voltage.

With properly adjusted circuit values the instantaneous D. C. peak voltage produced by the passage of an object through the electric field associated with said electrode may be on the order of several hundred volts. This allows the control device associated with the amplifier-oscillator to be adjusted for maximum stability at low sensitivity. For example, a gas filled discharge tube may be adjusted to operate on a voltage differential on the order of less than 1 volt, but such adjustment is critical and such a device must of necessity make use of precision construction to maintain a fair order of stability. For example, the effects of temperature, voltage change, etc., must be compensated for if close regulation is desired. In the present invention, the arrangement is such that no D. C. control voltage is normally present on the control grid of the gas filled discharge tube used as the controlling means. The passage of an object through the electric field associated with the control electrode may produce a voltage surge of, for example, 200 D. C. volts. For this condition the gas filled discharge tube can be adjusted to ionize at, for example, 25 D. C. volts. For this condition, the entire device is exceptionally stable in operation and almost totally independent of variations in voltage, temperature and other variable factors.

A further advantage of the present invention is that the design and operation of the control electrode is such that it may be concealed within the playing board so that no visible registration means are noticeable to the player, such construction also having the further advantage of providing a perfectly smooth playing surface, it being understood that the control electrode may also be so mounted as to be visible to the player without offering any obstruction to the passage of the playing ball.

This invention will be best understood in consideration of the following detailed description, in view of the accompanying drawings forming a part of the application. Nevertheless, it is understood that the invention is not confined to the disclosure, being susceptible to such changes and modifications as define no material departure from the salient features of the invention as expressed in the appended claims.

In the drawings:

Figure 1, section A represents a suitable amplifier for use in the practice of this invention; section B schematically represents a suitable electronic control circuit for use with the amplifier of section A; section C represents one part of the registration means normally employed in amusement devices of the class herein referred to; section D represents a partial view of the control electrode and the playing board in an amusement device.

Figure 2 represents an enlarged view of the control electrode installed flush with the surface of the playing board in an amusement device.

Figure 3 represents the electric field associated

with the control electrode for a condition where no object is in the electric field.

Figure 4 represents a modified view of the control electrode installed in the playing board where such electrode is installed below the surface to provide an unbroken playing surface.

Figure 5 represents the electric field normally associated with the control electrode for a condition where the playing ball has entered into the electric field.

Figure 6 shows diagrammatically an arrangement for dual operation.

Referring now to section A of Figure 1, vacuum tubes 1 and 13 represent a two stage amplifier, both tubes being here represented as pentodes, it being understood that any form of amplifier providing sufficient voltage gain may be used in the practice of this invention. I have found that a voltage gain on the order of 10,000 is practical, it being understood that any voltage gain producing the desired sensitivity may be used. Control grid 4 of vacuum tube 1 is connected to common ground terminal 24 through grid resistor 6, which may have a nominal value on the order of .5 megohm, and also by lead 39 to metallic electrode 46, connecting lead 39 being completely shielded by grounded shield 38.

Screen resistors 10 and 22, screen by-pass condensers 9 and 21, cathode resistors 8 and 20, cathode by-pass condensers 7 and 19, grid resistor 18, plate resistor 11, coupling condenser 12 and by-pass condenser 23 may all have a value determined by the particular type of tubes utilized for vacuum tubes 1 and 13, these values being in accordance with usual practice. Terminal 25 is the common B negative terminal, while terminal 26 is the B positive terminal.

The output of vacuum tube 13 is connected through transformer 27 to full wave rectifier tube 31. Transformer 27 is represented, for purposes of example, as an iron core transformer, having a primary winding 28 and a center tapped secondary winding 29-30, such transformer preferably having a stepup ratio on the order of 3:1 or higher, it being understood that the use of an iron core transformer is optional. The design of transformer 27 will largely determine the feedback frequency and, for the purposes of this invention, a medium audio frequency, such as, for example, 4000 C. P. S., provides sufficient sensitivity with good stability. It is understood that other frequencies may be used without departing from the principles disclosed by this invention.

Full wave rectifier 31 is represented as a vacuum tube, it being understood that other forms of rectifier may also be used, and that a half wave rectifier may be used in place of the full wave rectifier shown. While the half wave rectifier will produce a somewhat higher control voltage, it has the disadvantage of being less reliable at high playing speeds, as it is only operative every other half cycle and for that reason the frequency of oscillation must be maintained high enough to provide trigger action at the highest playing speed contemplated. With a full wave rectifier the only limitation on playing speed is the ionization time of gas filled discharge tube 72, which is normally on the order of 2 microseconds.

The D. C. output voltage of rectifier 31 is present across load resistor 33 which is in turn bypassed by condenser 32 and this voltage is available at terminals 36 and 37 with a polarity as indicated.

The feedback connection is shown connected

to terminal 30 of the secondary winding of transformer 27, it being understood that terminals 29 and 30 may be reversed to secure the proper phase relation to produce oscillation. This feedback voltage is in series with coupling condenser 35, which may normally have a capacity on the order of .006 mfd., and the value of this voltage available at the feedback electrode 41 is determined by the setting of potentiometer 34, the center tap 10 of potentiometer 34 being connected to a metallic electrode 41.

Referring now to section D of Figure 1, where the playing board is represented by 43 and the playing ball by 42, which may be considered as traveling in the direction indicated by the arrow. The entire electrode assembly as represented by sections 44, 45, and 46 is countersunk flush with the surface of the playing board, where 46 is the input electrode, which may comprise a thin strip 20 of metal, for example, a section having a thickness on the order of $\frac{1}{32}$ inch and a width of $\frac{1}{8}$ inch, so mounted that the $\frac{1}{32}$ inch edge is presented at the playing surface. 44 represents a grounded metallic shield completely enclosing 25 three sides of input electrode 46, and the insulation interposed between input electrode 46 and grounded metallic shield 44 is represented by the solid lines 45.

The output or feedback electrode comprises a 30 metal plate 41 normally mounted under the playing board. The actual dimensions of electrode 41 are non-critical, an average width for such electrode being on the order of 1 inch. Feedback electrode 41 is also shielded on the lower 35 side by metallic shield 40, it being understood that metallic shield 40 is insulated from feedback electrode 41.

The entire control electrode structure as 40 represented by numerals 44, 45, and 46 of section 45 D in Figure 1 is a compact assembly, which may, for purposes of example, have overall dimensions of $\frac{1}{8}$ inch wide, $\frac{1}{4}$ inch deep and a length determined by the width of the playing board, it being understood that while this electrode structure is shown as a straight line, for purposes of example, that such electrode may be made in any desired shape, such as, for example, semi-circular, angular, etc. A more complete description of the structure of electrode 44, 45, and 50 46 is given further below in connection with Figures 2 and 4.

Referring now to section B of Figure 1, which 55 represents the electronic control circuit normally associated with the amplifier schematically illustrated by section A of Figure 1 and previously described. In section B, 72 represents a gas filled discharge tube having a control grid 75 connected in series with condenser 79 to positive control voltage terminal 36 and a cathode 60 76 connected to the negative control voltage terminal 37. Plate 73 is connected to a source of positive voltage 26 in series with normally closed contacts 52, current limiting resistor 69 and relay 70. Suppressor grid 74 is biased negative in respect to cathode 76 by a source of voltage 80, having a polarity as indicated. Sensitivity is controlled both by the adjustment of voltage 80 and the setting of grid resistor 77, it being understood that other methods of sensitivity control may be used.

For any given value of plate voltage E_p and any given value of negative suppressor grid voltage E_s , a definite value of positive control grid voltage E_c will be required to ionize gas filled 75 discharge tube 72.

For a condition where no playing ball is in the electric field associated with the control electrode, no positive D. C. voltage will be present on control grid 75. Any small D. C. voltage which may result from external magnetic or electrostatic pickup, normal circuit voltage, secondary electron emission, etc., is broken by condenser 79. However, for a condition where playing ball 42 passes through the electric field associated with the control electrode, an instantaneous voltage is produced which will appear as a D. C. voltage E_g . This voltage pulse will occupy a time interval much greater than the ionization time of gas filled discharge tube 72, for any practical playing speed. For example, I have found that the circuit arrangement here given by way of example is reliable at playing speeds on the order of 40 feet per second, which is considerably in excess of playing speeds normally used.

It is characteristic of all gas filled discharge tubes that where a D. C. plate voltage is used the grid loses control after the tube is ionized. This is so in the present instance, and gas filled discharge tube 72 remains ionized after the control voltage E_g has returned to zero. However, ionization of gas filled discharge tube 72 allows the tube to draw plate current which results in the operation of relay 70, thus closing normally open contacts 71, which in turn energize the magnet 50 of the stepping switch illustrated in section C of Figure 1, said magnet 50 being energized from a source of voltage 48 and 49.

Referring now to section C of Figure 1, a self-interrupting stepping switch is illustrated. Operation of relay 70 energizes magnet 50, thus operating armature 54 and momentarily opening normally closed contacts 52, which momentarily removes the D. C. voltage from the plate 73 of gas filled discharge tube 72 and restores the circuit to the standby position, ready to operate on the next impulse received by the passage of an object through the electric field associated with the control electrode.

The balance of the stepping switch illustrated by section C of Figure 1 is the form usually employed in an amusement device, where 58 is the armature fulcrum, 59 the armature return spring, 56 the pawl associated with ratchet 60, 55 the pawl spring, and 53 an insulating stud controlling operation of contacts 52. The detent is represented by 51, the wiper shaft by 57, and the wiper arm by 61. In part, the contacts are represented by the figures 62, 63, 64, 65, 66, 67, and 68, which are in turn connected to any desired registration means 47 for example, illuminated figures.

The operation as just described requires only the use of a single electrode 44, 45, and 46, together with the associated feedback electrode 41, where registration would be secured regardless of the direction of travel of playing ball 42. However, it is readily apparent to those skilled in the art that two such electrodes may be used where each electrode is associated with a separate amplifier, a separate gas filled tube and a separate stepping switch. This dual operation will be similar to that described for single operation, except that the operation of the first stepping switch is arranged to lock out the second stepping switch for a period of time equivalent to the time required for the first stepping switch to operate and release. This time is ordinarily on the order of .15 second.

If two electrodes similar to electrode 44, 45,

and 46 and two feedback electrodes similar to electrode 41 are placed relatively close to each other in a horizontal plane, such as, for example, an edge to edge distance of 1 inch, for any practical condition, the playing ball will cross both electrodes in a time considerably less than .15 second. A reasonable time required for playing ball 42 to cross the 1 inch distance between two such electrodes would be on the order of .005 second. For this condition, playing ball 42 will register on the first electrode contacted but not on the second, but the second electrode will again be free to register in approximately .15 second. It is obvious to those skilled in the art that such an arrangement is applicable to high speed operation where numerous playing balls are traveling in both directions, and that registration would be in accordance with the direction of travel.

Referring now specifically to Fig. 6, the above described multiple operation is shown in detail where electrodes 46 and 46^a, 41 and 41^a represent the multiple electrode structure. All reference numerals are identical with those used in Fig. 1, with all plain numerals associated with amplifier A, control circuit B, and stepping switch unit C, and all numerals carrying the suffix ^a associated with amplifier A', control unit B' and stepping switch unit C'.

Normally closed contacts 85 are in series with the operating circuit of electro-magnet 50^a of stepping switch C', while normally closed contacts 85^a are in series with electro-magnet 50 of stepping switch C, this arrangement being such that the operation of stepping switch C will momentarily open the operating circuit for stepping switch C', and likewise the operation of stepping switch C' will momentarily open the operating circuit for stepping switch C, so that only one stepping switch may be in the operative position at any given instant.

The arrangement shown follows usual practice in the stepping switch contact arrangement, it being understood that other arrangements may also be practical and that any number of such stepping switches, together with the associated amplifiers and control circuits, may be used and so arranged that only one of said stepping switches may be operated at any given instant.

Referring now to Figure 2, an enlarged view is shown of the control electrodes, all reference numerals being the same as those used in connection with Figure 1. In addition to the detail disclosed by Figure 1, the insulating section 81 is clearly shown interposed between feedback electrode 41 and feedback electrode shield 40. Connection 39 is connected to control grid 4 of vacuum tube 1 of Figure 1 and connection 85 is the feedback connection made to feedback control 34 of Figure 1. It is believed that Figure 2 plainly shows the construction of the control electrode and that Figure 2 is self-explanatory.

Referring more specifically to Figure 4, the same electrode structure is represented except that in Figure 4 the electrode is installed below the playing surface of playing board 43, so as to present a smooth and unbroken playing surface 82. The distance X may be any value desired, a practical value being on the order of $\frac{1}{2}$ inch, it being understood that as the distance X is increased the sensitivity is decreased. However, for a small distance X , for example, on the order of $\frac{1}{2}$ inch, there is only a slight decrease in sensitivity and for a larger distance X , for example, on the order of $\frac{1}{8}$ inch, circuit values may be adjusted for increased sensitivity.

Referring now to Figure 3 a skeleton view of the electrode structure is represented where the broken lines 83 diagrammatically represent the electric field lines associated with the control electrode structure, it being understood that such electric field lines do not necessarily have a circular shape as represented by the broken lines 83. For a condition where playing ball 42 is outside of the electric field 83, very little energy is fed back from electrode 41 to electrode 46, due to the effects of shield 44 and shield 40. The actual amount of feedback energy for this condition may be controlled by adjusting feedback control 34 and, in any event, the steady DC control voltage developed from any such residual feedback will not act to trigger gas filled discharge tube 72, due to the continuous nature of such voltage.

Maximum sensitivity is realized when all values are so adjusted that minimum feedback exists between feedback electrode 41 and input electrode 46. However, the device is operative for any condition where the feedback relationship between feedback electrode 41 and input electrode 46 is less than maximum, maximum feedback as a steady state condition representing zero sensitivity.

Referring now to Figure 5 which is a skeleton view similar to Figure 3, except that playing ball 42 is now in the electric field, as represented by the broken lines 84. This electric field is now distorted by the momentary presence of playing ball 42, so that additional energy is transferred from feedback electrode 41 to input electrode 46. If playing ball 42 is moving at any practical speed, this increase in feedback will result in a D. C. voltage pulse which will act to trigger gas filled discharge tube 72 and cause the passage of playing ball 42 to be suitably registered, as previously described in detail.

The operation of the invention herein described is independent of the speed of travel of the playing ball, for any practical speed, is insensitive to the influence of external forces, is economical to construct and reliable in operation. Normally, close control of plate voltage is not necessary in order to produce reliable operation. The device as herein described is sensitive only to the passage of a playing ball, or other object which may be used in carrying out the purposes of an amusement game of the class herein referred to, it being of no practical importance whether such object is metallic or non-metallic.

False registration cannot be caused by the effects of body capacity. The actual effect of such body capacity is to lower the effect of feedback due to the additional shielding represented by such body capacity. However, this effect is not great enough, in any practical design, to cause failure of proper registration. By way of example, I have so adjusted circuit values that a D. C. peak voltage of 25 volts is necessary in order to produce ionization of gas filled discharge tube 72. For this condition, I have found that an average D. C. peak voltage of 250 volts is produced by the passage of a $\frac{1}{2}$ inch steel ball traveling at 20 feet per second. A maximum possible effect of body capacity may lower this instantaneous D. C. peak voltage to a value on the order of 75 volts but this lowered value is still 300% greater than the value needed to cause ionization of gas filled discharge tube 72, and the minimum value of 25 D. C. volts required is sufficiently high that false operation is improbable from transients, voltage fluctuations, etc.

I claim:

1. In an electronic control system including a registering means adapted to be activated by a control circuit responsive only to a control voltage in excess of a predetermined value, a pick-up electrode and a feed back electrode, an amplifier having an input circuit connected to the pick-up electrode and an output circuit connected to the feed back electrode, means partially shielding the pick-up electrode from the feed back electrode to restrict the amount of energy feed back from the output circuit to the input circuit of the amplifier, adjustable means controlling the degree of feed back normally to prevent oscillation of the amplifier when no object is present in the field between said electrodes, the coupling between said electrodes being increased by the presence of an object in the vicinity of the electrodes sufficiently to cause said amplifier to oscillate, and
- 20 means for supplying the control circuit with a control voltage in excess of said pre-determined value from the increased voltage output of the oscillating amplifier when an object is present in said field.
2. In an electronic control system including registering means adapted to be activated by a control circuit responsive only to a control voltage in excess of a predetermined value, a pair of spaced external electrodes, an electronic amplifier having an input circuit connected to one of said electrodes and an output circuit connected to the other of said electrodes, means shielding at least one of said electrodes to restrict the feed back from the output circuit to the input circuit of the amplifier substantially to prevent oscillation of said amplifier when no object is present in the field between said electrodes, the increase in energy feed back between said electrodes due to the presence of an object in the field between said electrodes causing said amplifier to oscillate, said control circuit including a gas-filled electronic tube normally non-conducting, a rectifier operatively connected to the output circuit of the oscillator, and means for supplying to the 45 gas-filled tube a rectified voltage pulse from said rectifier in excess of the threshold voltage of said gas-filled tube when an object passes through the field between said electrodes.
